UNITED STATES PATENT OFFICE.

ROBERT GORTON, OF BROOKLINE, MASSACHUSETTS; CHARLES W. NOYES ADMINISTRATOR OF SAID ROBERT GORTON, DECEASED.

METHOD OF MAKING GARTERS.

1,352,258.

Specification of Letters Patent. Patented Sept. 7, 1920.

Application filed October 7, 1919. Serial No. 329,078.

To all whom it may concern:

Be it known that I, ROBERT GORTON, a citizen of the United States, residing in Brookline, in the county of Norfolk and 5 State of Massachusetts, have invented certain new and useful Improvements in Methods of Making Garters, of which the following is a specification.

This invention relates to gentlemen's garters of the class in which the stocking-engaging clasp members are connected with the leg-band by clasp-suspending devices secured to a pad or pads arranged between the ends of the leg-band. This kind of garter is commonly called a "pad garter," and the object of my present invention is to provide a new method of making a garter of this class which is provided with two pads and clasps adapted to engage the stocking 20 at different points.

In my United States Patents Nos. 1,325,716 and 1,325,717 of Dec. 23, 1919, I have shown, described and claimed a new pad garter and a method of making the 25 same in which the garter is provided with a single pad. My present invention relates to the manufacture of garters in which each garter is provided with two pads and two suspending-clasps and in which certain features of my previous inventions are embodied in connection with other new features.

The garter made in accordance with my present invention comprises two pads made 35 from strip material, spaced apart and carrying clasps at their lower ends, the pads being connected with a horizontal leg-band member arranged between them from which the pads extend downwardly. Each of the 40 pads has a leg-band part made from the strip material which extends upwardly from the pad and which is connected with the remainder of the leg-band.

The method of the present invention 45 briefly stated, consists in folding the outer portions of a strip of material on the middle portion thereof, joining the end portions to the middle portion by transverse lines of stitches, extending the portions of the strip 50 at each end to form a portion of the leg-band, and then flattening the loop at each end of the blank and securing it to the free end and to the middle portion of the strip.

In the accompanying drawings:

55 Figure 1 is a perspective view of a double

pad garter made in accordance with my invention.

Figs. 2 to 8 inclusive, illustrate the method of making such a garter.

Fig. 2 shows a strip of material from 60 which the pad and leg-band or portions thereof may be made.

Fig. 3 shows a step of the method which consists in folding the opposite end portions of the strip upon the middle portion 65 thereof and in securing the two layers of material near each end by a diagonal line of stitches.

Fig. 4 shows the next step in the process which consists in bending the free ends of 70 the strip on diagonal lines of stitches.

Fig. 5 shows the succeeding step in which the loops formed at each end of the blank are flattened to define the pads and bring them into proper relation with the leg-band 75 parts.

Fig. 6 shows how the clasp members are associated with the pad portions of the garter.

Fig. 7 is a rear view of the parts shown 80 in Fig. 6.

Figs. 6 and 7 illustrate how the lines of stitches are disposed after the strip is bent, folded and arranged and after the clasp members have been associated with the pads. 85

Fig. 8 illustrates a blank that may be used, in which those parts of the strip which afford material for the pads are expanded or made wider than the other portions of the strip.

Fig. 9 is a perspective view of a garter made from the blanks shown in Fig. 9.

In Fig. 1, A indicates the pads, B the leg-band, and C, C' the tabs which may be considered parts of the leg-band. D indicates clasps with stocking-engaging members of well known construction, and E the suspending devices therefor which are attached to the garter. F indicates the usual slide or take-up and G the fastening devices or cast-off.

In the garter of my prior patents, leg-band portions extend upwardly and outwardly from the opposite sides of the pad. In the double pad garter, a leg-band portion extends upwardly and outwardly from the outside of each pad, and the two remaining leg-band portions unite or are united or connected to form a horizontally arranged leg-band portion connecting the 110

pads. Each pad instead of being arranged vertically is inclined downwardly and outwardly from its upper end so that the two pads extend downwardly from the leg-band 5 in divergent directions.

In the manufacture of the garter, I employ a strip of material, 1, which is of sufficient length to form the pads and the entire leg-band or those portions of the leg-band 10 which connect the pads with each other and which extend sidewise from the pads. Such a strip is indicated in Fig. 2 and this strip is so treated as to have its opposite end portions folded upon the middle portion 15 thereof in the manner indicated in Fig. 3, and the folded portions are joined at each end by a diagonal line of stitches 2 in such manner as to produce loop portions 3. After this, the free or end portions 4 of the strip 20 at each end are extended to provide leg-band portions. The loop portions 3 are then flattened in the manner indicated in Fig. 5 and in so doing the pads 5 are produced, and these are of substantially the same 25 shape and construction as those shown in my prior applications. The clasps D are then associated with the pads, the clasp-suspending tapes being attached to the pads by lines of stitches which are indicated 30 in Figs. 6 and 7. When thus folded and stitched, the pads will be inclined in the manner before described and will be connected by a horizontally arranged member 6. A fastening device G is applied to 35 the tab C' and the leg-band portion C may be attached to the rear leg-band portion B, shown in Fig. 1. It is obvious that the rear leg-band portion may be applied or connected with the pads and the take-up and 40 fastening devices or cast-off may be applied either before or after the folding operations before mentioned. Preferably the pads and the parts immediately associated with them are made of double faced tubular material, 45 as is common in pad garters of this kind.

In my application for patent Serial No. 329,072 filed October 7, 1919, I have shown and described how pad garters may be made

from strip material in which the width of the strip is not uniform, but which is wider 50 in those parts from which the pad or pads are made.

In Figs. 9 and 10 of the accompanying drawings I have illustrated how a double pad garter may be made from a strip having expanded or widened pad forming parts. Inasmuch as the method of folding, stitching, etc. is the same as that heretofore described, it is not necessary to further describe the construction of the garter shown 60 in Figs. 9 and 10 or its method of manufacture, but such a garter made from the expanded or widened material, has advantages over those before described inasmuch as in this way larger pads may be produced 65 and yet the leg-band parts may be narrow or of the same width as corresponding parts in garters made from strips of material of uniform width.

I claim as my invention:—

1. The method of forming a garter, which consists in folding the opposite end portions of strip material upon the middle portion thereof, joining the folded portions at each end by a transverse line of stitches, extending the free portion of the strip at each end to form a part of the leg-band, and then flattening the loop at each end and securing it to the free end and to the middle portion of the strip.

2. The method of forming a garter, which consists in folding the opposite end portions of strip material upon the middle portion thereof, joining the folded portions at their opposite ends by diagonal lines of stitches, 85 extending from one longitudinal edge of the strip inward to the opposite edge thereof, extending the free portion of the strip at each end to form a part of the leg-band, and then flattening the loop at each end and 90 securing it to the free end and to the middle portion of the strip.

In testimony whereof I have hereunto subscribed my name.

ROBERT GORTON.
